DESIGN FOR A DRESS ENSEMBLE

Simon Etkin, New York, N. Y.

Application December 5, 1938, Serial No. 81,570

Term of patent 3½ years

To all whom it may concern:

Be it known that I, Simon Etkin, citizen of United States, residing at 230 West 38th Street, in the county of New York and State of New York, have invented a new, original, and ornamental Design for a Dress Ensemble, of which the following is a specification, reference being had to the accompanying drawing, forming part thereof.

Fig. 1 is a front view of a dress ensemble showing my new design;

Fig. 2 is the back view thereof;

Fig. 3 is a side view of a sleeve member of the coat of the dress ensemble, as shown in Figs. 1 and 2;

Fig. 4 is a front view of a dress unit of the dress ensemble as shown in Figs. 1 and 2, and Fig. 5 is a rear view thereof.

The characteristic feature of my design resides in the combination on the ensemble disclosed of the specific puff stitched embroidery on the sleeves of the coat member and around the neck line of the dress section as shown.

I claim:

The ornamental design for a dress ensemble, substantially as shown and described.

SIMON ETKIN.
